WALL COVERING TILE ATTACHED BY TAPE

Reynold C. Beck, Jamaica, N. Y.

Application-October 5, 1946, Serial No. 701,596

1-Claim. (Cl. 72—19)

1.

This invention relates to a wall covering consisting of individual tiles which are mounted upon a wall by means of tapes which are affixed to the wall by an adhesive. The tiles and the tapes have cooperating fastening means in the form of snap fasteners so that after the tapes have been pasted upon the wall, the tiles are put into place by pressing the tiles against the tapes and the male fastening member on the back of the tile then engages the female fastening member on the tape, and the tile is then securely fastened to the wall.

The tiles are made of a suitable plastic composition of any known type or formula, heat and water resisting, and adapted to be molded or formed by compression. The tiles are very thin, perhaps about one sixteenth of an inch in thickness but this dimension is not critical. The tile is rectangular, preferably square and two sides of the tile have their edges bent back to form flanges for overlapping adjacent tiles.

The invention contemplates that the tiles are formed in suitable molds or dies and so formed, pressed and shaped that the tile comes from a machine as a finished article. The invention also proposes that the fastening means on the tile, either the male or the female member of a snap fastener, be inserted into the plastic material during the manufacture of the tile, so that the fastening means become an integral part of the tile. The latter is preferably curved very slightly from one edge to the opposite edge. When the tile is pressed against the tile to engage the fastening means thereon, the tile is straightened or flattened and inasmuch as it has an inherent tendency to resume its original slightly curved formation, the fastening means become more firmly engaged and the overlapping edges of the tiles are forced together.

The fastening means on the tape may be in the form of eyelets having spaced wires forming a spring clip adapted to receive and grip the fastening means on the tile. A relatively strong firm woven or otherwise fabricated tape is provided with an adhesive on the back so that by moistening the adhesive, the tape is firmly attached to the wall. The tape will be made in rolls to be cut off in suitable lengths.

The invention provides a wall covering suitable for use in the home, stores, buildings, decorative and like other purposes. Both the tiles and the tapes are adapted for mass production by automatic machinery so as to be relatively inexpensive to use and adapted for use by unskilled labor. In the accompanying drawing illustrating the invention

2.

Fig. 1 is a face view of the tile.

Fig. 2 is a sectional view taken on the line 2—2 of Fig. 1.

Fig. 3 is a side view of Fig. 1 looking from the right.

Fig. 4 is a sectional view taken on the line 4—4 of Fig. 1.

Fig. 5 is a side view of Fig. 1 looking from the bottom.

Fig. 6 is a view of a portion of the tape showing the fastening means thereon.

Fig. 7 is an enlarged sectional view of the tile and tape with the fastening means engaged and the tape affixed to a wall.

Fig. 8 is a detail showing the overlapping of the tiles.

Fig. 9 illustrates how a wall is covered with the tiles by building from the left and working toward the right.

Fig. 10 is a similar view showing the work being done by working from the right toward the left.

Fig. 11 shows a detail of staggered tiles.

Referring first to Figures 1—5, the tile 1 is rectangular, preferably square in form. Two adjoining sides 2 and 3 are bent or depressed to form flanges 4 and 5, respectively, which lie in a plane below or behind the plane of the surface of the tile. The flanges are cut away as at 6 and 7 to make room for the flanges of adjacent tiles as the tiles are being put into place. The tile is preferably slightly curved as shown in Figures 2 and 3.

A male fastener member 7 is secured in the center of the tile. As best seen in Figure 7, the fastener 7 has a stem whereby it is secured in the tile material as the latter is molded and pressed. The stem projects from the back of the tile and has a head 8. The latter may be of rectangular formation slightly longer horizontally than vertically as seen in Figure 1 so that the tile may be adjusted horizontally without the fastener members becoming disengaged.

The tape 10 is of suitable material and width and at spaced intervals equal to the height of the tile, the tape is provided with female fasteners. The latter may be in the form of eyelets 11 which support spaced wires 12. The latter are arranged to permit the head 8 of the tile fastener to be forced between the wires 12 as the tile is pressed against the tape and so that the wires grip the stem 7 in the manner of a snap or button fastener. Figure 7 shows the head 8 and the wires 12 in engagement to secure the tile to the tape. The latter is provided with an adhesive 13 for pasting the tape to the wall 14, Fig. 7.

A wall is covered as follows: As shown in Figure 9, the tape 10 is first cut into suitable lengths as may be required for the space to be covered. The tapes are moistened and pasted on the wall. When the tapes are thoroughly dry, the tiles may be pressed into position. The tapes are positioned on the wall so that the lowermost fastener 11 is a distance from the floor equal to half the height of the tile. Horizontally the tapes are spaced so that the distance between the fasteners 11 is 10 equal to the width of the tile. The first tile 15 may be pressed into position by a pressure sufficiently to flatten the tile and cause the fastener members to engage. It will be noted that the flanges 4 and 5 are at the right and the top of the tile 15. The next tile 16 may then be attached by placing it adjacent to the tile 15 and overlapping the flange 4. Then the tile 17 is placed and so on to complete the bottom row of tiles.

Then the tile 18 may be put into place and when secured the tile will overlap the top flange 5 of the tile 15. Then tile 19 may be placed and so on. Of course, one may build the wall covering vertically first if so desired. The tiles 20 and 21 are shown in positions about to be added to the other tiles so that the invention may be fully understood. The side flanges 4 lie underneath the adjacent horizontal tiles. The top flanges 5 lie underneath the tiles immediately above. By overlapping the tiles vertically, Fig. 8, moisture is prevented from running down behind the tile below.

If one desires to start building the wall from the right, the tiles are turned as shown in Fig. 10 with the flange 5 vertical and the flange 4 horizontal. In this view the tiles 23 and 24 are about to be placed next to the tile 22.

The tiles 25 may be staggered as shown in Fig. 11 by placing the tapes closer together and spaced so that the fasteners 11 will receive the fasteners 7. If the remaining space to be covered is less than the size of a tile, the tile may be cut off to suit. The tiles may also be of different sizes, not shown. For example, the tiles 16 and 19 in Fig. 9 may well be wider or narrower than the other tiles, the tapes being spaced to correspond.

It will be noted that in Fig. 7 the wires 12 in the eyelet 11 are flush with the front of the tape to provide space behind the wires for the head 8 of the fastener 7. The head 8 should preferably project from the back of the tile only sufficient to engage the wires in order that the back of the tile may come as close as possible to the front of the tape and the wall 14.

The space to be covered with the tiles may be

of any size. It may be horizontal, vertical or inclined. The work may be started from the bottom or from the top, or from either side. It should also be noted that if through error a tape is not placed in the proper spaced position on the wall, the error is quickly corrected by cutting away the wrongly placed portion and simply use a shorter piece of tape instead. The tiles may be cut by a pair of shears to fit corners and smaller spaces.

I claim:

A wall tile covering comprising in combination a plurality of thin inherently flexible wall tiles and a plurality of tapes affixed to a wall supporting said tiles thereupon, each of said tiles having a fastener projecting from its rear surface in the center of the tile, each of said tapes having members embedded therein and spaced along the tape, the members receiving said tile fasteners to support the tiles in adjoining overlapping wall covering formation with the rear surfaces of the tiles engaging the front surfaces of the tapes, each of said tiles being rectangular in shape and of initially outwardly curved formation flattened into wall covering position by manual pressure exerted against its front surface to force said tile fastener into permanent engagement with said receiving member on the tape, each of said tiles having adjoining edge portions of two adjoining sides depressed and engaging under the non-depressed edge portions of two adjoining tiles, said tapes being affixed to the wall in parallelism spaced a distance apart equal to the width of a tile.
